DESIGN FOR A TOOTHBRUSH DISPLAY
STAND

Alvin H. Meyer, Chicago, Ill.

Application August 26, 1946, Serial No. 132,867

Term of patent 7 years

(Cl. D80—9)

To all whom it may concern:

Be it known that I, Alvin H. Meyer, a citizen of the United States, residing at Chicago, in the county of Cook and State of Illinois, have invented a new, original, and ornamental Design for a Toothbrush Display Stand, of which the following is a specification, reference being had to the accompanying drawing, forming a part thereof.

Figure 1 is a front view of a toothbrush display stand embodying my new design;

Figure 2 is a top view thereof;

Figure 3 is a side view of the upper portion thereof;

Figure 4 is a vertical sectional view of the base thereof to illustrate the contour; and

Figure 5 is a vertical sectional view of the inter-

mediate portion thereof to illustrate the contour.

I claim:

The ornamental design for a toothbrush display stand substantially as shown.

ALVIN H. MEYER.
